(57) **CLAIM**

The ornamental design for a glove, as shown and described.

DESCRIPTION

FIG. 1 is a top front perspective view of a glove, showing our new design;

FIG. 2 is a front elevation view thereof;

FIG. 3 is a rear elevation view thereof;

FIG. 4 is a right-side elevation view thereof;

FIG. 5 is a left-side elevation view thereof;

FIG. 6 is a top plan view thereof;

FIG. 7 is a bottom plan view thereof;

FIG. 8 is a section view of FIG. 2; and,

FIG. 9 is a section view of FIG. 2.

The broken lines consisting of evenly spaced lines in the drawings depict parts of the glove that form no part of the claimed design. The broken lines consisting of dash-dot-dash lines in the drawings depict the boundary of the claim and form no part of the claimed design.

1 Claim, 5 Drawing Sheets
